(57) **CLAIM**

The ornamental design for a mop pad, as shown and described.

DESCRIPTION

FIG. 1 is a top perspective view showing a first embodiment of my new design for a mop pad;

FIG. 2 is a left side elevational view of the design of FIG. 1, wherein a right side elevational view is identical to the left side elevational view;

FIG. 3 is a front elevational view of the design of FIG. 1, wherein a rear elevational view is identical to the front elevational view;

FIG. 4 is a top plan view of the design of FIG. 1;

FIG. 5 is a bottom plan view of the design of FIG. 1;

FIG. 6 is a top perspective view showing a second embodiment of my new design for a mop pad;

FIG. 7 is a left side elevational view of the design of FIG. 6, wherein a right side elevational view is identical to the left side elevational view;

FIG. 8 is a front elevational view of the design of FIG. 6, wherein a rear elevational view is identical to the front elevational view;

FIG. 9 is a top plan view of the design of FIG. 6; and, FIG. 10 is a bottom plan view of the design of FIG. 6.

The broken lines in the drawings depict portions of the mop pad that form no part of the claimed design. A pair of curved lines in FIGS. 6-10 depict broken away symbols and form no part of the claimed design.

The dashed curved break lines shown in FIGS. 6 and 8-10 are symbolic breaks indicative of a variable distance therebetween, and the appearance of any portion of the mop pad between the break lines forms no part of the claimed design.
